CABLE GUIDE

Filed April 7, 1928

FIG. 1.

FIG. 2.

Inventor

Charles Brassington

By Watson E. Coleman
Attorney

UNITED STATES PATENT OFFICE.

CHARLES BRASSINGTON, OF JOLIETT, PENNSYLVANIA.

CABLE GUIDE.

Application filed April 7, 1928. Serial No. 268,284.

This invention relates to a cable guide and has relation more particularly to a device of this kind especially designed and adapted for use in connection with a slope structure, and it is an object of the invention to provide a guide of this kind comprising two rotatably supported rollers operatively connected in a manner whereby said rollers have rotation in opposite directions under the influence of the ascending cable whereby the rollers run at cable speed with very little wear on either the rollers or cables.

The invention consists in the details of construction and in the combination and arrangement of the several parts of my improved cable guide whereby certain important advantages are attained and device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary view in top plan illustrating a cable guide constructed in accordance with an embodiment of my invention and in applied position;

Figure 2 is a view partly in front elevation and partly in cross section of the structure as illustrated in Figure 1.

As disclosed in the accompanying drawing, T denotes the trackways of a slope structure of any preferred type and disposed transversely of the track structures T are the shafts 1 rotatably supported by the bearings 2. A shaft 1 extends inwardly of a trackway T and said shaft 1 at a point substantially midway of the rails of the trackway has fixed thereto a roller 3. The shafts 1 are spaced apart in a direction lengthwise of the trackways T and the inner extremities of the shafts 1 terminate between the trackways and are in driv-

ing connection one with the other by the constantly meshing pinions 4 fixed to the inner end portions of said shafts 1. The slope cables associated with the trackways T have contact with the rollers 3 from above and in practice the ascending cable will effect the desired rotation of both of the rollers 3 but in reverse directions with the peripheral speed of the rollers 3 being equal to the cable speed thereby substantially eliminating wear on the slope cables and also on the roller 3.

From the foregoing description it is thought to be obvious that a guide cable constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A cable guide for a slope structure comprising rotating shafts disposed in a direction transversely to the travel on the slope structure, rollers fixed to the shafts and with which the slope cables are adapted to engage and constantly meshing pinions carried by the shafts to cause said shafts to rotate in unison but in reverse directions.

2. A cable guide for a slope structure comprising rollers spaced apart in a direction transverse to the travel on the slope structure, and an operative connection between said rollers to cause the same to rotate in unison and in opposite directions.

In testimony whereof I hereunto affix my signature.

CHARLES BRASSINGTON.
